UNITED STATES PATENT OFFICE.

CLINTON G. WILDERSON, OF LEETONIA, OHIO, ASSIGNOR TO THE CRESCENT MACHINE COMPANY, OF LEETONIA, OHIO, A CORPORATION OF OHIO.

ROTARY CUTTER HEAD.

Application filed May 29, 1924. Serial No. 716,628.

The present invention relates to rotary cutter heads such as are employed in jointers, planers, and similar wood working machines.

5 In the patent to Harrold, No. 1,153,910, Sept. 21, 1915, there is disclosed a rotary cutter head having provision for accurately adjusting the individual knives without removing the knives from their seats. In the 10 construction shown in this patent, the knives are firmly held in adjusted position by means of throat pieces and cooperating wedge blocks and thrust screws arranged in tapered sockets communicating with the 15 knife receiving seats. When it is desired to adjust a knife, the thrust screws cooperating therewith are loosened to release the knife from the clamping pressure of its throat piece, and the knife is then adjusted 20 outwardly by means of a tool inserted successively in openings intersecting the knife receiving seat, the tool having a lug arranged to engage the inner edge of the knife and move the same outwardly upon rotation 25 of the tool. A difficulty encountered in this method of adjustment is to hold the knife in its adjusted position until the thrust screws are tightened up. By the present invention I have provided simple 30 and effective means for overcoming this difficulty.

Certain preferred embodiments of my invention are illustrated in the accompanying drawings, in which:—

35 Figure 1 is a view in elevation of a rotary cutter head embodying one form of the invention,

Figure 2 is a section taken on the line II—II of Figure 1,

40 Figure 3 is a section taken on the line III—III of Figure 1,

Figures 4 and 5 are sections similar to Figure 3 showing two different modifications of the invention,

45 Figure 6 is an elevation of a tool for adjusting the knives, and

Figures 7 and 8 are, respectively, a plan view and side elevation of one of the wedge blocks.

50 In the construction illustrated the body 2 of the cutter head has a plurality of knife receiving seats 3 extending longitudinally thereof and outwardly tapering sockets 4 communicating with the seats, a plurality of these sockets being associated with each

seat. Arranged in each seat is a knife blade 5 and a throat piece 6, the latter constituting a holding bar for the knife blade. Each knife blade is of the ordinary form and provided with the outer beveled cutting edge 7, and is adapted to be held flat against one side wall of its seat 3 by the throat piece or holding bar 6, which latter flatly and solidly bears against one side face of the knife blade. The face of the throat piece 65 opposite that in engagement with the knife blade has a flange 8 projecting therefrom, the said flange being located at the inner edge of the throat piece and being received in a groove 9 communicating with the seat 70 3. The interlocking engagement between the flange 8 and groove 9 serves to lock the throat piece against outward displacement when the parts are assembled while, at the same time, permitting the throat piece to 75 be readily removed without sliding it endwise from its seat when the knife blade is removed.

Arranged in each of the sockets 4 is an outwardly tapered wedge block 10 having a 80 threaded bore therethrough, as shown at 11, to receive a thrust screw 12, which is adjustable in said bore and bears against the bottom of the socket. The said thrust screw has an angular recess 13 to receive an actuating tool. When the thrust screws associated with a knife blade are turned in one direction the cooperating wedge blocks will be forced outwardly, thus causing the throat piece 6 to clamp the knife blade between 90 the throat piece and a wall of the knife receiving seat.

The body 2 of the cutter head is provided with a suitable number of bearing holes 14 which pierce the body at substantially right angles to the knife receiving seats 3, and each of the latter has a suitable number of such holes associated with and in communication with the same. These bearing holes are preferably of a cylindrical form and are 100 adapted to receive a cylindrical adjusting wrench or implement 15 having an operating handle 16 at one end and having a lug 16' projecting from the opposite end and adapted to engage the inner edge of a knife blade, whereby, when the tool is rotated the said lug will exert a lifting action on the knife blade, causing it to be moved outwardly. In adjusting a knife blade by means of this tool, the tool will be inserted 110

in each of the holes 14 intersecting the knife seat and turned to move the blade outwardly the required amount as determined by a gauge, for example, of the type shown in the patent to Harrold, above referred to.

The construction so far described is identical with that disclosed in the patent to Harrold. In adjusting a knife blade in this manner the thrust screws 12 associated with the blade must first be turned in a direction to permit the cooperating wedge blocks to be moved inwardly sufficiently to release the knife blade from the clamping action of the throat piece. When this is done difficulty is experienced in holding the knife blade to its adjusted position until the wedge blocks can again be moved into clamping engagement with the throat piece. When the adjusting tool is inserted in one of the holes 14 and the blade moved outwardly at that point to bring the knife edge into engagement with the gauge, this adjustment is apt to be lost while the blade is being further adjusted by the operation of the tool in another hole, and when the blade has finally been adjusted to the correct position, it is apt to slip inwardly before the wedge blocks can be tightened up. By the present invention this difficulty is overcome by the provision of yielding means for holding the knife blade after it has been released from the clamping pressure due to the engagement of the wedge blocks with the throat piece.

One form of my invention is shown in Figures 1, 2 and 3. Each throat piece has a number of holes 17, for example 2, drilled transversely thereinto from the face of the throat piece opposite that which engages the knife blade. These holes extend only part way through the throat piece and arranged in each of them is a coil spring 18 which bears, at one end, against the bottom of the hole, and at its other end against a wall of the knife receiving seat. These springs serve to thrust the throat piece against the knife blade and yieldingly clamping the latter between the throat piece and a wall of the knife receiving seat when the wedge blocks are loosened. This yielding clamping of the knife blade permits the latter to be adjusted, but at the same time exerts sufficient friction between the faces of the knife blades and the wall of the knife receiving seat and the cooperating face of the throat piece to hold the knife from slipping out of its adjusted position before the wedge blocks can be tightened up.

In the modified form of the invention shown in Figure 4 the holes 17^a extend entirely through the throat piece so that the springs 18^a bear at one end directly against the knife blade and at the other end against a wall of the knife receiving seat.

In the modified construction shown in Figure 5, the holes 17^b extend into the throat piece from that face thereof which engages the knife blade, so that the springs 18^b bear at one end directly against the knife blade and at the other end against the bottoms of the holes.

The advantages of the invention will be readily apparent to those skilled in the art since it provides a simple, cheap and effective means for holding the knife blades in adjusted position when the positive clamping pressure, due to the co-action of the wedge blocks with the throat pieces, is relieved, thereby facilitating the adjustment of the blades and shortening the time required for such adjustment.

I claim:

1. A rotary cutter including a body member having a longitudinally extending slot therein, a cutter in the slot, a throat member in the slot between one wall of the slot and the cutter, and means for yieldably urging the cutter into engagement with the other wall of the slot.

2. A rotary cutter including a body member having an axially arranged slot therein, a cutter in the slot, a throat member in the slot between one wall of the slot and the cutter, and resilient means associated with the throat member for urging the cutter against the other wall of the slot.

3. A rotary cutter of the class described including a body member having an axially extending slot therein, a cutter in the slot, a throat member in the slot for cooperation with the cutter and interposed between the cutter and one wall of the slot, adjustable wedges in the body for cooperation with the throat member for holding it in clamping engagement with the cutter, said body having transverse pockets therein extending into and terminating at the bottoms of the slots, and resilient means associated with the throat member for exerting pressure against the cutter when the wedge members are moved to releasing position with respect to the throat member.

In testimony whereof I have hereunto set my hand.

CLINTON G. WILDERSON.
